UNITED STATES PATENT OFFICE.

CHARLES F. LA FOLLETTE, OF HIGHLAND, CALIFORNIA, ASSIGNOR OF ONE-HALF TO WALTER DU B. BROOKINGS, OF HIGHLAND, CALIFORNIA.

ROTATING WOODWORKING-CUTTER.

No. 901,626.

Specification of Letters Patent.

Patented Oct. 20, 1908.

Application filed July 18, 1907. Serial No. 384,473.

To all whom it may concern:

Be it known that I, CHARLES F. LA FOLLETTE, a citizen of the United States, residing at Highland, in the county of San Bernardino and State of California, have invented a new and useful Rotating Woodworking-Cutter, of which the following is a specification.

This invention relates to improvements in 10 rotating cutter-knives.

The objects of this invention are to increase the efficiency and durability of rotary cutters used for planing and molding machines, and to simplify the adjustment as 15 well as the replacement of the blades.

Another object of my invention is to provide a cutter composed of parts separable from each other in order that as the bit becomes worn or broken or in any manner un- 20 fit for use, it can be replaced readily and quickly, while at the same time rendering the replacement compact, stable, and free from any vibration.

With these objects in view the invention 25 consists in the features and details of construction, as well as in the combination of parts as will be described in connection with the accompanying drawing, and then be more specifically pointed out in the 30 claims.

The invention consists in a two-part knife comprising a bit and bit-holder dove-tailed together face to face, bifurcated at one end and beveled toward one side at the other end, 35 the sides of said knife being flat except at said beveled portion; the object being to provide for sharpening the bit or thin blade which is dove-tailed into the bit holder or backing, so that the knife is solid, free from 40 vibration, and readily handled, inserted, adjusted, and withdrawn from the ordinary cutter-head.

In the drawing, Figure 1 shows an under- 45 side view of the knife; Fig. 2 is a transverse section on lines x^2-x^2 , Fig. 1; Fig. 3 is a top plan view; and Fig. 4 a transverse section on lines x^4-x^4 , Fig. 3. Fig. 5 is a perspective view showing the knife attached to a cutter head.

50 1 designates the bit-holder consisting of a bifurcated blade having on one face a longi-

tudinal, dove-tailed groove 2 extending from end to end thereof to receive a bifurcated cutting blade forming the bit 3, the edges of which blade are beveled to fit the dove-tail groove 2 of the bit-holder. The edges of the furcations of the knife are parallel, thus to form between said furcations a straight slot 4 to fit a screw 5 the head of which extends over the furcations, and by 60 means of which the knife is adjustably clamped to the rotary cutter-head 6 so that by loosening the screw the knife may be slid bodily forward or backward on the head as may be required, and may be removed entirely from the cutter-head; and the bit may be slid along the groove to adjust the cutting edge thereof relative to the edge of the bit-holder. The knife is arranged to be fixed or adjusted to the rotary cutter-head 6 which 70 may be supplied with one or a plurality of knives, each knife being fixed to the head by suitable screws in the same manner as shown at 5 in Fig. 5.

The cutter blade portion or bit 3 extends 75 beyond the forward portion of the backing or bit-holder 1, the two portions being beveled in an equal degree, the object of this arrangement being to provide for sharpening a thin blade without interfering with 80 the backing while the knife remains solid, free from any vibration, and readily handled, inserted, adjusted, and withdrawn from the stock of an ordinary cutter head. Now as these lips or cutting edges are necessarily reduced in length whenever sharpened, the release of the screw will allow the knife to be slid further out and will also allow adjustment of the bit along its holder until the length of the slotted portion 4 has been 90 reached when, of course, the bit, and in time the entire knife is no longer useful. In case the bit wears out before its holder, a new bit may be applied to the holder.

Having thus described and ascertained the 95 nature of my invention, what I claim is:

1. A rotary head, a flat cutter-head knife consisting in two blades dove-tailed together face to face, bifurcated at one end and beveled toward one side at the other end, and 100 mounted on said cutter-head, and a screw in the cutter-head engaging the inside walls

of the furcations of the knife, and provided with a head engaging said furcations.

2. A cutter-head knife consisting in two blades dove-tailed together face to face, bi-
5 furcated at one end and beveled toward one side at the other end, the sides of said knife being flat except at such beveled portion.

In testimony whereof, I have hereunto set my hand at Highland California this 22nd day of May 1907.

CHARLES F. LA FOLLETTE.

In presence of—

W. G. WILMS,

F. H. WELTON.
